(57) **CLAIM**

The ornamental design for a reagent container, as shown and described.

DESCRIPTION

FIG. 1 is a top and side perspective view of a reagent container according to a first embodiment;

FIG. 2 is a bottom and another side perspective view of the reagent container according to the first embodiment;

FIG. 3 is a side view of the reagent container according to the first embodiment;

FIG. 4 is another side view of the reagent container plate according to the first embodiment;

FIG. 5 is a top view of the reagent container according to the first embodiment;

FIG. 6 is bottom view of the reagent container according to the first embodiment;

FIG. 7 is a top and side perspective view of a reagent container according to a second embodiment;

FIG. 8 is a bottom and another side perspective view of the reagent container according to the second embodiment;

FIG. 9 is a side view of the reagent container according to the second embodiment;

FIG. 10 is another side view of the reagent container plate according to the second embodiment;

FIG. 11 is a top view of the reagent container according to the second embodiment; and,

FIG. 12 is bottom view of the reagent container according to the second embodiment.

The broken lines immediately adjacent to the claimed subject matter represent the bounds of the claim, all other broken lines represent the environment. None of the broken lines form part of the claimed design.

1 Claim, 6 Drawing Sheets
